(57) **CLAIM**

The ornamental design for a power inlet box, as shown and described.

DESCRIPTION

FIG. 1 is a perspective view of a power inlet box design in a closed state, showing my new design.

FIG. 2 is a front view of a power inlet box.

FIG. 3 is a rear view of a power inlet box.

FIG. 4 is a left side view of a power inlet box.

FIG. 5 is a right side view of a power inlet box.

FIG. 6 is a top view of a power inlet box.

FIG. 7 is a bottom view of a power inlet box.

FIG. 8 is a perspective view of a power inlet box in an open state; and,

FIG. 9 is a front view of a power inlet box in an open state. The broken lines shown in the drawings are for the purpose of illustrating portions of the power inlet box that form no part of the claimed design.

Any shading and cross-hatching are not features of the design but are utilized to illustrate the surface contours of the power inlet box design in the drawings.
